F. J. KLINE,
PAPER FASTENER,
APPLICATION FILED DEC. 4, 1919.

1,378,242.

Patented May 17, 1921.

INVENTOR
Fred J. Kline
BY
Charles D. King
ATTORNEY

UNITED STATES PATENT OFFICE.

FRED J. KLINE, OF NEW YORK, N. Y.

PAPER-FASTENER.

1,378,242.

Specification of Letters Patent.

Patented May 17, 1921.

Application filed December 4, 1919. Serial No. 342,421.

To all whom it may concern:

Be it known that I, FRED J. KLINE, a citizen of the United States, and a resident of New York, in the county New York and

5 State of New York, have invented certain new and useful Improvements in Paper-Fasteners, of which the following is a specification.

10 This invention relates to paper fasteners and particularly to tongued paper fasteners in which the tongues are passed through papers or documents and through holes in a retaining member or washer and then bent down on said member.

15 The main object of the invention is to provide improved means for guarding the bent down tongues, so that they shall not catch on other articles such as papers and the like, after they are bent down on the retaining member.

20 My improvements embody a member to cover the bent down tongues, particularly the ends of the same, and also embody suitable means to secure the covering member 25 to the paper fastener. The covering member is so arranged that its edges come close to the said retaining member and prevent papers or other articles from catching between the two members.

30 The means I prefer to employ for accomplishing the above object are illustrated in the drawing accompanying and forming part of this specification and in which—

35 Figure 1 is a plan of a paper fastener embodying my invention.

Fig. 2 is a longitudinal section of the same on the line 2—2 of Fig. 1.

Fig. 3 is a transverse section on the lines 3—3 of Figs. 1 and 2.

40 Fig. 4 is a plan of a modified form of my invention.

Fig. 5 is a transverse section on the line 5—5 of Fig. 4.

Fig. 6 is a plan of a modified form of retaining member or washer.

Fig. 7 is a transverse section on the line 7—7 of Fig. 6.

Fig. 8 is a plan of another modification of my invention.

50 Fig. 9 is a transverse section on the line 9—9 of Fig. 8.

Fig. 10 is an end elevation of the covering member 6 of Figs. 1, 2 and 3.

Fig. 11 is a plan of the covering member 6 of Figs. 1, 2 and 3. 55

Fig. 12 is an end elevation of the covering member of Figs. 4 and 5.

Fig. 13 is a plan of the covering member of Figs. 4 and 5.

Fig. 14 is an end elevation of the covering member of Figs. 8 and 9. 60

Fig. 15 is a plan of the covering member of Figs. 8 and 9, and

Fig. 16 is an end elevation of another modification of the covering member. 65

Like characters refer to like parts in all the figures of the drawing.

In Figs. 1, 2 and 3, I have illustrated my improved paper fastener applied to a file of papers, such as letters or documents, and 70 indicated by the letter F. The said paper fastener comprises a member 2 having tongues 3 which are adapted to be pushed through the file of papers F and to project on top of the same. A member which I 75 term a retaining member or washer, is indicated by the numeral 4, and is provided with holes or perforations 5. The said member 4 is placed on the file with the tongues 3 passing through the holes 5 and 80 the tongues 3 are then bent down as indicated in Figs. 2 and 3. The member 4 is provided with means for securing a third member, which I term a covering member, and which may be of any suitable form. A 85 type of covering member which I find very convenient to use is illustrated in Figs. 1, 2, 3, 10 and 11. The covering member is designated by the numeral 6, and in this form it has a concave curved surface 7 at the bottom 90 and a convex curved surface 8 at the top.

Any suitable means may be provided for securing the covering member 6 to the member 4, and a type of such means is illustrated in Figs. 1, 2 and 3, consisting of four overhanging projections or lugs 9, one near each of the four corners of the member 4. Such lugs or projections are adapted to guide and hold the edges 10 of the covering member 6 when it is placed in position as indicated 100 in Figs. 1 and 3. The covering member is placed in position by sliding it endwise between and under the ends of the lugs or projections 9 until it comes to the position illustrated in Fig. 1. It will be seen in Fig. 3 that the tongue 3 is entirely covered

and that the edges 10 of the covering member 6 meet the top surface of the retaining member or washer 4, so that no loose papers or other articles can catch underneath and 5 be caught by the file.

In Figs. 4, 5, 12 and 13, I have illustrated a modified form of my invention in which the covering member 6 is flat on top at 11, and provided with a groove 12 at the bottom in which the tongues 3 are held. Flanges 13 are provided, one on each side, by means of which the covering member is guided and held in position in co-operation with the means on the retaining member 4.

In Figs. 4 and 5, the means I provide for holding the covering member consist of overhanging portions 14 of considerable length, and having a cross-section resembling that of the lugs of Fig. 3.

In Figs. 6 and 7 is illustrated a modified form of the type of retaining member seen in Fig. 1. Six lugs 9 are provided, three on each side, one being placed at the central part, so that when the covering member is 25 in place, the fastener is materially stiffened.

In Figs. 8 and 9 the retaining member 4 is provided with ridges 15, one near each longitudinal edge, and in the inner parts of said ridges are the lugs or holding members 30 9. A plain flat strip 6', shown in detail in Figs. 14 and 15, is used as a covering member.

The plain flat covering strip 6' can be used with any of the other forms of retaining member when desired, if it is desired to 35 reduce manufacturing costs. The form for most economical manufacture of those illustrated comprises the retaining member of Fig. 1 with the covering member of Figs. 40 14 and 15. Fig. 16 is an end elevation of a type of covering strip which has been stiffened by forming a ridge 16 at the middle of the cross-section, and extended throughout or nearly throughout its length.

45 What I claim is:—

1. The combination with a member embodying two spaced apart tongues adapted to be pushed through papers, of a flat retaining member having two holes through 50 which the tongues can be passed and bent down flat on the retaining member and two pairs of sloping projections struck up from the interior part of the retaining member and each having an overhanging portion

toward the central part of the retaining member, and a tongue-covering member adapted to slide under the overhanging portions of said projections and be held thereby and cover the tongue ends. 55

2. The combination with a member having two spaced apart tongues adapted to be pushed through papers, and a retaining member having two holes through which the tongues can be passed and bent down flat on said member, of a covering member 60 for the tongue ends, and a plurality of oppositely-placed, sloping abutments on said retaining member between the two holes, struck up from the interior part of said member, and between which abutments the 65 covering member can slide and be held, said members being arranged with a space between the retaining member and the covering member in which the tongue ends can lie and be covered by the covering member. 70

3. The combination with a member embodying two spaced apart tongues adapted to be pushed through papers, of a retaining member having two holes through which the tongues can be passed and bent down flat 80 on the retaining member and two pairs of projections struck up from the interior part of the retaining member, one pair near each end, and a tongue-covering member adapted to be passed under and held by said projections with its side edges in contact with the 85 upper surface of the retaining member.

4. The combination with a member having two spaced apart tongues adapted to be pushed through papers, and a retaining member having two holes through which the tongues can be passed and then bent down flat on said member, of a covering member having its upper surface curved 90 transversely from its central part to its side 95 edges, and a plurality of pairs of hooks on said retaining member, between the two holes therein, struck up from the interior part of said member, and between which the covering member can slide endwise and be 100 held, covering the tongue ends, with its side edges in contact with the upper surface of the retaining member.

Signed at New York City in the county of New York and State of New York this 105 1st day of December, A. D. 1919.

FRED J. KLINE.
